BAKER'S COOLING RACK

Kurt Christoffersen, Norwich, Conn., assignor to The Artistic Wire Products Co. of Connecticut, Incorporated, Taftville, Conn., a corporation of Connecticut

Filed Jan. 22, 1964, Ser. No. 78,318

Term of patent 14 years

(Cl. D44—29)

FIG. 1

FIG. 2

FIG. 3

FIG. 4

FIG. 5

FIG. 6

FIG. 1 is a perspective view of a baker's cooling rack showing my new design, wherein the foot members form substantially plane, closed geometric configurations with respect to the end stringer;

FIG. 2 is a top plan view thereof;

FIG. 3 is an edge elevational view;

FIG. 4 is a side elevational view, showing the foot members as disclosed in FIG. 1;

FIG. 5 is a side elevational view showing another form of cooling rack wherein the foot members form substantially a curvilinear acute triangle with respect to the end stringer;

FIG. 6 is a side elevational view showing another form of cooling rack wherein the foot members form a right triangle with respect to the end stringer.

The essential features of my design reside in the provision of two base members having foot forms as shown, in combination with superposed transverse stringers, the short ends of the base members being outwardly disposed with respect to the end stringers, all as shown.

I claim:

The ornamental design for a baker's cooling rack, as shown and described.
